Primary Examiner — Cathron Brooks*Assistant Examiner* — Daniel J Domino*74) Attorney, Agent, or Firm* — Banner & Witcoff, Ltd.(57) **CLAIM**

The ornamental design for a display screen with icon, as shown and described.

DESCRIPTION

FIG. 1 is a front view of a display screen with icon showing the new design;

FIG. 2 is a front view of a display screen with icon showing an alternative embodiment of the new design;

FIG. 3 is another front view of the display screen with icon, showing an additional element in broken line; and,

FIG. 4 is another front view of the display screen with icon, showing two additional elements in broken line.

The broken lines illustrate a portion of a display screen, and form no part of the claimed design.
